UNITED STATES PATENT OFFICE.

ERNST F. PRIDDA, OF CHICAGO, ILLINOIS.

PACKAGE-CARRIER.

SPECIFICATION forming part of Letters Patent No. 736,631, dated August 18, 1903.

Application filed January 12, 1903. Serial No. 138,656. (No model.)

To all whom it may concern:

Be it known that I, ERNST F. PRIDDA, a citizen of the United States, residing at Chicago, in the county of Cook and State of Illinois, have invented a new and useful Improvement 5 in Package-Carriers, of which the following is a specification.

My invention relates particularly to carrying devices for use in carrying tied packages; 10 and my primary object is to provide a device of this character of exceedingly cheap and simple construction, which may be readily applied to a package, and which will not slip when in use.

15 The invention is illustrated in the accompanying drawings, in which—

Figure 1 represents a side elevational view of a package with my improved carrier applied thereto; Fig. 2, an end view of the carrier; Fig. 3, a side view of the carrier; Fig. 4, a similar view of a modification; Fig. 5, a similar view of another modification, and Fig. 6 an enlarged broken detail perspective view.

25 A represents a package, B a cord by means of which the package is secured and which has a longitudinal loop b and a transverse loop b', and C the improved carrying device. (Shown in Figs. 1 to 3, inclusive.) The device

30 C is preferably formed of sheet metal and comprises a base portion c, equipped at its lower edge with lateral upturned hooks c', vertical side members c², formed integrally with the base portion, and a handle c³, formed integrally with the portions c². As shown, the handle is formed by stamping the metal through and rolling it up, thereby affording a space c⁴ for the fingers. In this form the hooks c' are four in number. The two intermediate hooks are separated by the short space c⁵ and the end hooks are provided with struck-in projections c⁶. As thus described, there is provided a longitudinal channel c⁷ for the longitudinal cord of the tie, and the

45 prongs c⁶ serve to prevent displacement of the carrier when the latter is allowed to drop upon the package. I also provide at the ends of the bottom of the channel c⁷ longitudinal cord-gripping slots c⁸, which also aid in preventing shifting of the device, as will be understood from Fig. 1.

In the form just described the carrier is

applied to the package by laying it flat upon the package longitudinally thereof, with the hooks down and the intermediate hooks on opposite sides of the transverse loop of the cord, and the device is then moved to bring the longitudinal loop of the cord within the channel of the hooks, after which the device is righted, thus causing the transverse loop to draw the longitudinal loop downwardly between the intermediate hooks to prevent shifting of the handle, as will be understood readily from Fig. 1.

In the modification of Fig. 4, C' represents the carrier, and the construction is the same as that described, except that the hooks are two in number instead of four in number.

In the modification of Fig. 5, C² represents the carrier, and the construction is similar to the other constructions, except that the hooks are six in number. An advantage of this construction is that the carrier may be located at any suitable position upon the package to balance the package. For instance, the cross-loop of the cord may come at the space d at one side of the center of the carrier, as shown in this figure, so that if one end of the package is heavier than the other or the cross-loop does not come at the center of the bundle the carrier may be adjusted to compensate.

The carriers may be cheaply formed by stamping from sheet metal or other suitable material and may be rattled to take off the edges. If desired, advertising matter may be applied to any available space on the carrier. The retainers c⁶ may be of any desired number, length, and cross-section.

Changes in details of construction within the spirit of my invention may be made. Hence no undue limitation should be understood from the foregoing detailed description, which has been given for clearness of understanding only.

What I regard as new, and desire to secure by Letters Patent, is—

1. A device of the character described, comprising a suitable handle, a base portion connected therewith, and a plurality of laterally and upwardly turned hooks located at one side of said base portion, for the purpose set forth.

2. A device of the character described, com-

prising a substantially rigid member having a handle, a base portion, connecting end members, and a plurality of laterally and upwardly turned hooks located on one side of said base portion and having a comparatively small space between two of said hooks, for the purpose set forth.

3. A device of the character described, comprising a channeled cord-receiving member 10 equipped with hooks, and a retainer coacting with one of said hooks.

4. A device of the character described, comprising a channeled cord-receiving member equipped with hooks, and a retainer projecting inwardly from one of said hooks.

5. A device of the character described, comprising a channeled cord-receiving member equipped with a plurality of laterally and upwardly turned hooks including a pair of intermediate hooks separated by a short space and a pair of end hooks, for the purpose set forth.

6. A device of the character described, comprising a sheet-metal member having a portion stamped out and curled upwardly to form 25 a handle and laterally and upwardly turned hooks formed integrally with the base portion of the member, for the purpose set forth.

7. A device of the character described, comprising a channeled cord-receiving member 30 having laterally and upwardly turned hooks separated by a central comparatively short space, whereat the transverse loop of a tie is received, for the purpose set forth.

8. A device of the character described, comprising a suitable handle with a cord-receiving channel having a bottom provided at its ends with longitudinal cord-gripping slots, for the purpose set forth.

ERNST F. PRIDDAT.
